UNITED STATES PATENT OFFICE.

ALBERT GEORGE GOODBODY, OF LOUISVILLE, KENTUCKY.

BINDING-POST FOR ELECTRIC CONDUCTORS.

SPECIFICATION forming part of Letters Patent No. 296,160, dated April 1, 1884.

Application filed November 30, 1883. (No model.)

To all whom it may concern:

Be it known that I, ALBERT GEORGE GOODBODY, of Louisville, in the county of Jefferson and State of Kentucky, have invented a 5 new and Improved Binding-Post for Electric Conductors, of which the following is a full, clear, and exact description.

My invention relates to improvements in binding-posts for connecting electric conductors; and it consists in the peculiar construction and arrangement of the parts, as herein-after more fully set forth, and pointed out in the claims.

Reference is to be had to the accompanying 15 drawings, forming a part of this specification, in which similar letters of reference indicate corresponding parts in all the figures.

Figure 1 is a longitudinal sectional elevation of my improved binding-post on the line 20 xx , Fig. 2. Fig. 2 is a cross-sectional elevation of the same on the line yy , Fig. 1. Fig. 3 is a sectional plan view of the same on the line zz , Fig. 2.

A standard, A, is secured on a base, B, 25 by a screw, C, screwed through the base into the lower end of the standard, with which screw the conducting wire or strip is connected. The standard A is provided at its upper end with an annular flange, a, or a 30 cross-piece, and on the standard a cap, D, is held loosely, which cap is pressed upward by a spiral spring, E, surrounding the standard A, and acting on an annular flange, d, or a cross-piece formed on the lower end of the 35 cap. In the upper end of the cap D a button or head, F, of insulating material is screwed or otherwise fastened. The standard A is provided with a longitudinal groove, G, into which the inner end of a pin, H, passes, which 40 is held in the flange d of the cap, and holds the cap from turning. The standard A is provided at its upper end with an aperture, J, and the cap D is provided with two opposite apertures, K, which can be brought in line with the aperture J. The flange a prevents the spring E from pressing the cap D upward too far, as the inner edge of the bottom flange, d, of the cap D rests closely against the standard A, and strikes against the bottom 45 edge of the flange a when the cap D is raised as far as possible. If the pin L, secured to the conductor, is to be held in the binding-post, the cap D is depressed until the apertures J and K are in line, and then

the pin L on the end of the wire is passed 55 through the said apertures and the pressure on the head is removed. The spring E presses the cap D upward, and the bottom edges of the apertures K in the cap, pressing the pin L or wire upward, press that part of the pin 60 6c or wire within the aperture J against the top of the aperture J, and the pin L or wire will thus be held in the binding-post. The flange d can be soldered or screwed on the lower end of the cap D to permit assembling the parts. 65

The above-described post is especially designed and adapted for use in medical batteries, for therapeutic batteries, and also for ordinary electrical purposes. The insulated top enables the physician or electrician to 70 change the current with greater facility while treating the patient, and without in any way diverting the current from the patient.

I am aware that a binding-post for electrical instruments, consisting of a chambered 75 post and a headed spring-pressed interior plug having its motion limited by a pin passing through a groove made in the chambered post and plug, has heretofore been employed; and I am also aware that a binding-post 80 capped at its upper end, provided with a hole for the passage of a wire near its upper end, and a spring-pressed collar for binding the wire, is old, and I therefore lay no claim to such inventions. 85

Having thus fully described my invention, I claim as new and desire to secure by Letters Patent—

1. The combination, with the binding-post A, provided with the peripheral longitudinal 90 groove G, of the spring-pressed cap D, provided with the perforated flange d, and pin H, passing through the perforation in the flange, and having its end resting in the groove G, to prevent the cap from turning, substantially as shown and described. 95

2. The combination, with the base B, screw C, binding-post A, provided with the peripheral longitudinal groove G, aperture J, and top annular flange, a, of the loose cap D, having the perforated bottom flange, d, apertures K, insulated button F, pin H, spring E, and pin L, substantially as shown and described. 100

ALBERT GEORGE GOODBODY.
